UNITED STATES PATENT OFFICE.

CLAUDE GRIVOLAS, OF ST. CLOUD, FRANCE.

ROTARY PENDULUM-BOB.

937,792.

Specification of Letters Patent. Patented Oct. 26, 1909.

Application filed January 17, 1908. Serial No. 411,352.

To all whom it may concern:

Be it known that I, CLAUDE GRIVOLAS, a citizen of the French Republic, residing at St. Cloud, in France, have invented a certain 5 new and useful Improvement in Rotary Pendulum-Bobs, of which the following is a specification.

Torsional pendulums hitherto constructed for working with a long swing have bobs 10 which perform a reciprocating rotary movement and are suspended by means of thin steel ribbons. The regulation of these pendulums is effected by means of external weights adapted to be adjusted relatively to 15 the center of the bob. This method has the disadvantage that the regulating device is exposed to dust and atmospheric influences.

The present invention provides a regulating device located in the interior of the 20 bob. This arrangement has the advantage that the regulating device is protected from external influences, and it also obviates error in the adjusting of the mechanism.

The invention is illustrated in the annexed 25 drawing, in which—

Figure 1 is an elevation of a torsional pendulum bob constructed according to the invention, Fig. 2 a vertical section of the 30 same, Fig. 3 a view of the cover or case thereof, with the base removed, Fig. 4 a top plan view of the base, and Fig. 5 a cross-section on the line 5—5 of Fig. 4.

The pendulum comprises a disk shaped 35 box or case comprising a cover A having a circular flange A² (Figs. 1, 2 and 3) and which may be swaged, cast or constructed of a cylindrical part soldered to a disk, and a base B which fits into said cover A. Within the case a cylindrical support or 40 block D is fixed to the cover thereof by means of a screw C, and a screw E passes from the said support through the top of the cover and serves for fixing to the latter an external part F, which may be of any 45 suitable ornamental design. To the top of the part F is attached the thin steel ribbon G by means of which the bob is suspended.

The block D is traversed by a steel spindle H screw-threaded outside said block, the 50 thread H¹ being a right-hand thread and the thread H² a left-hand thread. The spindle H has a circular groove H³ engaged by the part I of a bolt I¹ screwed into the block D, so that the spindle can be rotated but not longitudinally displaced.

With the threaded parts H¹ and H² of the

spindle there engage the internally threaded weights J¹ and J² adapted to be simultaneously moved to or from the center of the case A by rotating the spindle. For rotating the spindle a key is placed on the squared end H⁴ thereof. The flange A² has a small aperture A¹ for the insertion of the key, and two arrows are engraved adjacent this aperture, marked on the case with letters such as "R" and "A" respectively to indicate the directions in which the key must be turned for producing acceleration and retardation respectively (Fig. 1).

The preliminary or approximate regulation is effected by fixing weights K and K¹ 70 at the internal circumference of the base B, the said weights K and K¹ being preferably of lead and of the shape shown in Fig. 4 so that they do not interfere with the movements of the weights J¹ and J². The 75 weights K and K¹ are fixed by means of screws L L¹ which traverse the bottom cover B. The said weights are preferably covered by plates M and M¹ of the same shape as the 80 weights, consisting of copper or other rigid metal, and firmly held in position by means of screws.

Before the parts K, K¹, M and M¹ are placed in position the adjustable weights J¹ and J² are moved to their central positions, that is to say, positions half-way between the circumference and center of the case. The pendulum is then approximately regulated by adding to or subtracting from the 85 weights K K¹. Precise regulation is then effected by adjusting the weights J¹ and J² 90 in the manner hereinbefore described.

What I claim as my invention and desire to secure by Letters Patent of the United 95 States is:—

1. In a torsional pendulum bob for a clock movement, the combination of a hollow casing extending in the plane of oscillation and symmetrical about the axis of torsion, rough adjustment weights within said casing near the periphery thereof and symmetrical about the axis of torsion and fine adjustment weights movable to and from the axis of torsion also within the said casing.

2. In a torsional pendulum bob for a clock movement, the combination of a hollow casing extending in the plane of oscillation and symmetrical about the axis of torsion, rough adjustment weights within said casing near the periphery thereof and sym-

metrical about the axis of torsion, said weights being formed of parts separable in planes of oscillation, and fine adjustment weights movable to and from the axis of torsion also within the said casing.

3. In a torsional pendulum bob for a clock movement, the combination of a disk extending in the plane of oscillation, said disk having a cylindrical flange, and a cover disk, the whole forming a hollow casing symmetrical about the axis of torsion, rough

adjustment weights within said casing near the periphery thereof and symmetrical about the axis of torsion and fine adjustment weights movable to and from the axis of torsion also within the said casing.

In witness whereof I have signed this specification in the presence of two witnesses.

CLAUDE GRIVOLAS.
